COVER AND RECEPTACLE FOR DRY
PRINTING MACHINES

Willibald Martin, Binghamton, N. Y., assignor to
General Aniline & Film Corporation, New York,
N. Y., a corporation of Delaware

Application March 14, 1945, Serial No. 582,696

3 Claims. (Cl. 95—75)

1

This application pertains to an invention in dry printing machines, such as Ozalid machines for making reproductions of drawings, printed matter, etc., and more especially, to a cover for enclosing and protecting the sensitized material employed on such machines. The cover also has the function of receiving or holding large drawings or other originals to be printed.

The invention has for one of its objects the provision of a cover which is adapted to protect rolls of sensitized material supported at the front or other part of such a machine so that said sensitized material shall not be subjected to direct rays of sunlight or to light from other sources. It is a further object of the invention to so construct such a cover that it shall have the additional function of supporting large rolls or sheets of drawings or tracings, or other originals to be printed. A further object of the invention is that of so devising the combined cover and receptacle that when in a position to protect the sensitized material against direct light or from other damage, that it shall not interfere with drawing the sensitized material from the supply rolls and shall not make it necessary to take other than the usual steps to introduce or feed that paper across the feed board of the machine. Other objects will become apparent as the mechanism is described in greater detail.

The invention is herein described as applied to one of the larger types of dry printing machines, although it is to be understood that it is applicable to all such machines, no matter what their sizes, and in fact, it is applicable to all machines of this general description though the specific illustrations and description pertain to one only of them. Normally the sensitized paper and the original to be printed are fed across a feed board at the front of the machine and a roll or rolls of the sensitized material are mounted at the front of the machine below the feed board. In the machine herein illustrated, there is provision for two such rolls of sensitized material, but it is to be understood that the invention applies to constructions in which there may be only one roll or more than one. While diazo-type coated paper is not very sensitive to ordinary sources of light, especially the ordinary tungsten lighting to be found in most industrial plants, the rolls of sensitized material are sometimes in position on these machines for a considerable period of time in which very little of the material is printed, for example, when the machine is to be employed for making reproductions of smaller sizes for which cut sheets are employed. If the machine

2

is located so that direct sunlight strikes the rolls or if it is in position near artificial light having a greater percent of violet or ultra-violet than normal, then it may become more essential, or 5 at least, more desirable, to protect the printing material.

When printing larger tracings or other originals, considerable difficulty may be experienced in handling them, even though they are introduced to the machine after being rolled. Since the operator of the machine has to guide both the sensitized paper and the original to be printed into the machine, the original may be released in which event it will unroll and, if 15 long enough, part of it may reach the floor to be stepped on or possibly to become otherwise damaged. The cover may be lowered to a position as will hereinafter be described in which it serves as a receptacle or tray for such rolls of original material. At that time it does not serve as a cover for the light sensitive paper, but the paper is continuously being fed into the machine and no part of the same is exposed to the light for a period of time long enough to affect it in 20 any undesirable manner. If desired, a number of tracings may be rolled and held in the receptacle whereupon each may be printed in the order desired.

As will be described in greater detail, the combined cover and receptacle is adapted to be easily and effectively moved from one position to the other and is locked in one of its positions while it is maintained in the other by gravity. It may be very easily released and moved from one 30 position to the other. The invention will now be described in detail by reference to the accompanying figures of drawing in which:

Fig. 1 is a front elevation of part of a machine to which the invention has been applied.

Fig. 2 is a side elevation, certain parts being broken away, wherein the combined cover and receptacle is shown in each of the positions which it may occupy.

Fig. 3 is a detail of the cover and receptacle as 45 seen from one end.

Fig. 4 is a section taken at the line 4—4, Fig. 2.

Now referring to Figs. 1 and 2, the front portion of a dry printing machine of the type to which the invention may be applied is generally indicated by numeral 10. For a more complete description of such a machine, reference is made to U. S. Patent 2,308,130. The originals to be printed and the sensitized paper are fed into the machine across a feed board 11 which is located 50 at the front of the machine and at a convenient

height. Below this feed board and at either side are the projecting plates 12 and 13 between which are supported rolls of sensitized material, one of which is supported on the spindle or shaft 14 and the other of which is carried by shaft 15, although only one such roll may be mounted on some machines. The spindles 14 and 15 are supported at their left hand ends by bearings 16 and 17 which are suitably held within the plate 12. The other ends of the spindles are receivable within the bearings 18 and 19 bolted to the plate 13. The details of these spindles and bearings have not been shown since they are not important to the invention herein described and claimed. It is sufficient to say that the spindles are suitably frictioned so as to offer resistance against turning or other means is provided to tension the sensitized paper as it is drawn from the rolls, and that the spindles are removable from the bearings 18 or 19, as the case may be, for sliding a roll of paper into position. End plates, one of which is shown at 20, are removable from the spindles, are adjustable along them, and are secured in position by set screws or other suitable means. They are used to position the rolls of material centrally of the machine and to prevent displacement of that material.

As the paper is withdrawn from one or the other of the rolls, it is passed about a guiding roller 21 at the front of the board 11. It also passes over a cutting wire which extends beneath the roller 21 and is fixed at one end but attached to a spring 22 at the opposite end. That wire is employed for cutting any desired length of paper as it is fed into the machine, that being accomplished in a well-known manner.

In Fig. 2, the combined cover and receptacle is shown in two positions, one identified as a full line position, the other a dotted line position. In the full line position, the sensitized material is covered and protected against light or other damaging influences. In the dotted line position, the same device becomes a receptacle for rolls of original material as above described. This cover includes end pieces 23 and an arcuate or other connecting portion 24. The connecting portion 24 is preferably a strip of sheet material bent into proper curvature and welded or otherwise attached to the end pieces 23. The sheet material forming the part 24 is turned back upon itself at the top and bottom edges thereby strengthening the structure and rounding the edge so as to prevent damage to the paper as it is drawn over one of those edges, Fig. 2. The length of the sheet material forming part 24 is slightly less than the lateral space between the inner sides of plates 12 and 13. The ends 23 thus have a small amount of clearance within the plates 12 and 13. Each of those end pieces has an elongated opening or bearing 25 and a notch 26. The elongated openings 25 engage about the flanges 27 of the bearings 17 and 19. Thus the said flanges serve as supporting bearings or pivots on which the end pieces 23 may be rotated or upon which they may slide for a limited extent as determined by the length of the elongated openings. When in raised or covered position, the structure is pushed inwardly as shown in Fig. 2 and the flanges 27 bear against one end of the openings while the notches 26 engage beneath projecting studs 28, Figs. 2 and 4. These studs are held within the plates 12 and 13. Only one is shown, that at the plate 13, but it is to be understood that the opposite end pieces 23 is identical with that illustrated and that a notch 26 therein is similarly

engaged by a corresponding stud when the cover is in the full line position, Fig. 2.

When it is desired to employ the device for holding rolled tracings or other material, it is first raised slightly, then pulled outwardly and when the notches 26 have cleared the studs 28, is dropped to the position shown in dotted lines. Then it is sustained by contact of the opposite ends of the elongated openings 25 on flanges 27. Handles or knobs 29 are used to grip and control the device as it is moved from one position to the other. Of course, to return it to the full line position, it is merely necessary to raise the cover by pulling it forwardly and upwardly and then pushing inwardly until the notches 26 have engaged beneath studs 28.

As shown in Fig. 2, the sensitized material may be drawn from one of the rolls, about the upper edge of the cover strip 24, then over the cutting wire and about roller 21. As it is cut, the short end is left projecting and that end may be gripped and fed over the board 11 and into the machine when desired. If the lower roll of material is being used, the same applies. Thus it can be seen that the rolls of material are protected against light or other damage, yet such material is always ready to be fed to the machine whenever prints of a size requiring such larger material are to be made. In the event it becomes desirable to support large tracings or other originals, the combined cover and receptacle are quickly dropped to the lower position and serves its intended purpose in that position. The device is easily moved from one position to the other and is securely retained in upper position while it remains in the lower position due to the action of gravity upon it.

While one embodiment of the invention has been disclosed, it is to be understood that the inventive concept may be carried out in a number of ways. This application is, therefore, not to be limited to the precise details described, but is intended to cover all variations and modifications thereof falling within the spirit of the invention and the scope of the claims.

I claim:

1. In a printing machine of the type described, the combination of a feed table, supporting means for a roll of sensitized printing material positioned beneath the feed table over which that material is drawn from the roll and fed, and a combined sensitized material protecting cover and receptacle for original material to be printed, comprising light shielding end members and a connecting light shielding member extending from one end member to the other and along the length of the roll of sensitized material, means upon which said end members are pivoted comprising an elongated bearing in each end member and cooperating fixed pivots adjacent the supporting means for the roll about which the end members and the connecting member may be swung to a position in which the material is shielded and from that position to one in which the connecting member is substantially horizontal for retaining the material to be printed, and means to retain the said members in the first-mentioned position including a notch in one of said end members and a fixed stop engageable within said notch when the shielding means is raised and the end members moved inwardly to the extent permitted by their elongated bearings but being disengageable therefrom upon outward movement of said end members as permitted by the elongated bearings.

2. In a printing machine of the type described,

the combination of a feed table, supporting means for a roll of sensitized printing material positioned beneath the feed table over which that said material may be drawn from the roll and fed, and a combined sensitized material protecting cover and receptacle for original material to be printed, comprising light shielding end members and a connecting light shielding member extending from one end member to the other and along the length of the roll of sensitized material, said connecting light shielding members having an edge which when the member is in material protecting position, reaches to a point slightly beneath the said feed table so that the sensitized material may be threaded over that edge to be guided thereby as it approaches the feed table, means upon which said end members are pivoted comprising an elongated bearing in each end member and cooperating fixed pivots adjacent the supporting means for the roll about which the end members and the connecting member may be swung to a position in which the material is shielded and from that position to one in which the connecting member is substantially horizontal for retaining the material to be printed, and means to retain the said members in the first-mentioned position including a notch in one of said end members and a fixed stop engageable within said notch when the shielding means is raised and the end members moved inwardly to the extent permitted by their elongated bearings, but being disengageable therefrom upon outward movement of said end members as permitted by the elongated bearings.

3. In a printing machine of the type described, the combination of a feed table, supporting means for a roll of sensitized printing material positioned beneath the feed table over which that material is drawn from the roll and fed, and a combined sensitized material protecting cover and

receptacle for original material to be printed, comprising light shielding end members and a connecting light shielding member extending from one end member to the other and along the length of the roll of sensitized material, means upon which said end members are pivoted comprising an elongated bearing in each end member and cooperating fixed pivots adjacent the supporting means for the roll about which the end members and the connecting member may be swung to a position in which the material is shielded and from that position to one in which the connecting member is substantially horizontal for retaining the material to be printed, and means to retain the said members in the first-mentioned position including a cooperating notch and a fixed stop member, one in one of the pivoted end members and the other carried by an adjacent fixed portion of the machine, said notch and stop member being interengaged when the shielding means is raised and the end members moved inwardly to the extent permitted by their elongated bearings, but being disengageable, one from the other, upon outward movement of said end members as permitted by the elongated bearings.
